CLAIM

The ornamental design for a table as shown and described.

DESCRIPTION

FIG. 1 is a top front perspective view of a table showing our new design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
 FIG. 8 is a bottom view thereof.
 The broken lines in the figures show portions of the table
 that form no part of the claimed design.

1 Claim, 5 Drawing Sheets

Related U.S. Application Data

a continuation of application No. 29/685,929, filed on Apr. 1, 2019, now Pat. No. Des. 913,728, which is a continuation of application No. 29/590,454, filed on Jan. 10, 2017, now Pat. No. Des. 846,316, which is a continuation of application No. 29/522,911, filed on Apr. 3, 2015, now Pat. No. Des. 776,471.
